W. W. SLOANE

LOCOMOTIVE

Original Filed Jan. 21, 1922

FIG. 2

FIG. 3

INVENTOR:
WILLIAM W. SLOANE
BY: Clarence F. Poole
ATTORNEY

UNITED STATES PATENT OFFICE.

WILLIAM W. SLOANE, OF CHICAGO, ILLINOIS, ASSIGNOR TO GOODMAN MANUFACTURING COMPANY, OF CHICAGO, ILLINOIS, A CORPORATION OF ILLINOIS.

LOCOMOTIVE.

Application filed January 21, 1922, Serial No. 530,872. Renewed March 19, 1923.

To all whom it may concern:

Be it known that I, WILLIAM W. SLOANE, a citizen of the United States, residing at Chicago, in the county of Cook and State 5 of Illinois, have invented an Improvement in Locomotives, of which the following is a specification.

This invention relates to improvements in locomotives or trucks and has for its principal object to provide an improved construction affording relative flexibility of the supporting wheels and axles so as to readily follow uneven track.

In a copending application for U. S. Letters Patent, bearing Serial No. 487,376, filed July 25, 1921, now Patent No. 1,436,205, granted November 21, 1922, I have shown and described an equalizing device for the purpose above stated in which a flexible 10 connection between the journal boxes on opposite ends of an axle and the locomotive frame is provided by means of a pair of rocking members operatively connected together by a horizontally movable tie bar or rod. In the present application, I show another form of equalizing device in which the rocking members function in a manner similar to that disclosed in the copending application referred to, but in which the 15 relations of the supporting element, or journal boxes, and the supported element, or locomotive frame, are inverted with respect to each other, as will be more fully understood from the following description, having 20 reference to the accompanying drawings, in which

Figure 1 is a transverse cross-sectional view of a locomotive construction in accordance with my invention.

Fig. 2 is a fragmentary view taken on line 2-2 of Fig. 1.

Fig. 3 is a view showing a modified form in which my invention may be embodied.

In the drawings, the embodiment of my invention illustrated in Figures 1 and 2 includes a pair of side plates 2, 2, constituting a portion of the locomotive frame, and an axle 3 having a pair of supporting wheels 4, 4, thereon and provided with journal boxes 6, 6. Said journal boxes may be of any approved construction and are arranged to move vertically between guide plates or pedestals 7, 7, of the usual construction. A

motor enclosed in a casing 5 may be suspended on the axle 3 in any suitable manner to 55 provide motive power thereto.

Referring now to the novel features constituting my present invention, the locomotive frame is supported on journal boxes 6, 6, through the medium of an equalizing device comprising a supporting member 8 extending transversely of the locomotive above the axle 3 and provided with suitable spring seats 9, 9, at opposite ends thereof adapted to receive supporting springs 10, 10, 60 which engage the journal boxes 6, 6. In the embodiment illustrated the supporting member 8 has its central portion 8^a offset upwardly so as to pass above the motor casing 5. A pair of rocking members 11, 11, 65 are mounted each adjacent the side plate 2 of the locomotive frame. Each of said rocking members constitutes in effect a bell crank lever pivotally mounted to swing in a vertical plane transversely of the locomotive. 70 Each of said rocking members 11 has a center pivot 12 connected to the supporting member 8, a laterally extending arm 13, and an upwardly extending arm 14. The first mentioned arm 13 engages a suitable support 15 mounted on side plate 2 of the locomotive frame. In the form shown, the end of arm 13 has a curved bearing portion engaging the support 15 so as to permit both a rocking movement and a limited horizontal movement between the arm and support. 75 The upper arm 14 of the rocking member is pivotally connected to a tie bar or rod 16 extending transversely of the locomotive and having pivotal engagement with the similar 80 arm 14 of the rocking member 11 at the opposite side of the locomotive.

Among other forms in which my invention may be embodied, I have illustrated a modified form in Fig. 3 in which the arm 95 13 is pivotally connected to the side plate 2 by means of a pivot pin 18^a mounted in a suitable bracket 18^b secured to said plate 2. In this form the center pivot 12^a is secured in a horizontally extending slot 12^b so as 100 to permit relative movement of the parts during operation of the device. In other respects, the modified form shown in Fig. 3 is similar to that shown in Figs. 1 and 2.

In applying my invention to a locomotive 105 of the ordinary two-axle type, one support

ing axle is preferably mounted in the usual manner, that is to say, without an equalizing device, so as to provide the desired stability to the locomotive body.

5 From the above description, it will now be clear that the construction described in the present application operates on a similar principle to that disclosed in my copending application Serial No. 487,376 above referred to, excepting that the relations of the supporting element, or journal boxes and the supported element, or the locomotive frame are inverted with respect to each other. That is to say, in the present application, the center pivots of the rocking members are mounted on the supporting member 8 which supports opposite ends of the axles, and one end of each rocking member engages the locomotive frame to provide a support therefor. In the former form, the center pivots of the rocking members are connected to the locomotive frame and one arm of each rocking member is supported by adjacent journal boxes. On both forms a horizontally moveable connecting rod is used to transmit the motion of one rocking member to the other, and vice-versa.

10 The counterpart of cross member 8 of the latter form is found in the locomotive frame of the former, as both parts mentioned provide rigidly connected supports for the center pivots of the rocking members.

15 The construction forming the subject matter of the present application may be

used advantageously under many conditions and requirements of locomotive design.

20 I claim as my invention:

1. In a car, a frame, an axle, a rigid supporting member connected to opposite ends of said axle and movable vertically therewith respective to said frame, a pair of rocking members at opposite sides of the frame and interposed between said rigid member and said frame, and means operatively connecting said rocking members together. 45

2. In a car, a frame, an axle, a rigid supporting member connected to opposite ends of said axle and movable vertically therewith respective to said frame, a pair of rocking members at opposite sides of the frame 50 and interposed between said rigid member and said frame, and transversely movable means operatively connecting said rocking members together.

3. In a car, a frame, an axle, a rigid supporting member connected to opposite ends of said axle and movable vertically therewith respective to said frame, a pair of bell crank levers pivotally mounted adjacent opposite ends of said supporting member, each 55 having a laterally disposed arm in supporting engagement with the frame, and transversely movable means operatively connecting said bell crank levers together.

25 Signed at Chicago, in the county of Cook and State of Illinois, this nineteenth day of January, 1922.

30 WILLIAM W. SLOANE
